UNITED STATES PATENT OFFICE

EDWARD HUGETZ, OF NEW YORK, N. Y.

FOUNTAIN PEN

Application filed May 11, 1932, Serial No. 610,651, and in France November 12, 1931.

The present invention relates to a self-filling fountain-pen having an inner rubber ink sac. In most of the known fountain pens the rubber ink sac has a uniform cylindrical shape and its diameter uniform throughout its length is adapted to the narrowest part inside of the fountain pen barrel to prevent deformation of the ink sac and difficulties resulting therefrom preventing the proper filling of the fountain pen. If for instance the fountain pen barrel has an inner screw thread projection for the screw on cap, the rubber sac has heretofore been throughout of a size corresponding to the smallest inner diameter 5 of the barrel. If the fountain pen holder carries a pressure lever acting upon the ink sac there must be space for the lever and besides for the spring pressure bar resting therebetween; therefore in such case the diameter 10 of the rubber ink sac has been made uniformly of such a small diameter that said intermediate space was produced. In this way with the known fountain pens there has been lost a great deal of ink capacity.

According to the present invention, this drawback is overcome thereby that the ink sac is not shaped uniformly cylindrical throughout, but is adapted exactly to the shape of the inside of the fountain pen barrel. 15 In consequence thereof the ink sac for such fountain pen barrels which have a screw thread projection projecting into the inside of the barrel, have at this place an annular narrowing, whereas the parts of the ink sac being above and underneath the screw thread 20 projection are of a larger diameter and possibly fill out all the space of the inside of the fountain pen barrel. And with the fountain pen holders with a pressure lever the diameter of the ink sac is reduced only in its upper end 25 located next to the pressure lever and is enlarged again below the pressure lever to such an extent that it again completely fills the lower space of the fountain pen. By this use of the inside space of the fountain pen barrel it is possible to create the greatest possible space for ink storage. At the same time by varying the diameter of the ink sac the further essential advantage is attained thereby that the relatively long ink

sac is subdivided into several short parts, of which each offers a stronger resistance against deformation than the uniformly long rubber sac. If, for instance, by screwing on of a cap, the neighbouring end of ink sac 55 has the tendency to turn with the cap, such turning is eliminated with a subdivided ink sac, and it returns to its normal position much faster.

If inside the ink sac one of the known rigid 60 air tubes is placed, it is of advantage to extend said tube to the narrowed part of the ink sac, which is about the middle of the ink sac, that the air tube is not squeezed or damaged at the squeezing of the upper part of the 65 ink sac. The air tube the same as the ink sac can be made of elastic material and can be engaged with an inner extension of the pen section respectively upon the ink feed resting therein. In this case the air tube can be 70 longer without danger of being damaged by the pressing action.

At its upper end, the air tube can be enlarged funnel like and be fastened with its 75 enlargement inside the ink sac. For the returning of the ink from the upper into the lower part of the sac openings can be provided in the funnel shaped enlargement.

The drawing shows several sample constructions of the invention.

Fig. 1 is a longitudinal sectional view of 80 a fountain pen with a cap screwed on the threaded projection of the barrel, the narrowed part of the ink sac next to said projection and the rigid air tube located therein,

Fig. 2 shows in longitudinal section, the same fountain pen with flexible air tube, the funnel like enlarged upper end of which is fastened inside to the ink sac and provided with openings.

The fountain pen holder (Fig. 1) consists in the known manner of the lower part 1, into which is inserted the ink feed 2 carrying the writing pen 3. At its upper end the barrel has a screw thread projection projecting into 95 the inner space of the barrel, upon which projection the upper barrel part 5 is screwed on.

According to the invention the diameter of the ink sac is not throughout so uniformly 100

small as the one of the threaded projection 4. On the contrary the ink sac 6 is provided about its middle part with a restricted part 7, so that the spaces of the barrel having a larger diameter below and above the threaded projection are better utilized and each single short part of the sac—especially the upper one—offers a greater resistance against deformation or distortion and if one portion of such a subdivided sac is subjected to pressure it will assume its normal shape much quicker than a sac of the usual sac shape uniformly throughout.

The air tube 8 can be rigid as known; but in such case it is extended only to the restricted portion 7, so that it can not be squeezed or damaged at the squeezing of the upper part of the air tube.

According to Fig. 2 both the air tube 9 and the ink sac are made of one piece of flexible material for instance caoutchouc and the lower end is slipped over the extension 10 of the ink feed 2. The upper part of the air tube is provided with a funnel like extension 11 which extends into the ink sac and is provided with openings 12 through which, if necessary, the ink can reflow from the upper into the space 6.

At the squeezing of the upper part of the ink sac the air in the sac is expelled through the air tubes 8 and 9. On releasing the ink sac sucks up the ink. This operation is repeated until the sac is sufficiently filled.

What is claimed:

1. A fountain pen comprising an ink sac in its barrel having a restricted circumferential portion intermediate its ends the upper part of said ink sac adapted for manual compression after the removal of the cap avoiding the use of pressure bars and leaving a wide open communication between the squeezing area and the lower part of the sac to permit the storage of a large quantity of ink in comparison to the size of the barrel and the ready return of the sac to its normal shape after each compression, and an air tube in said ink sac.

2. A fountain pen comprising an ink sac in

its barrel having a peripheral restricted part subdividing the ink sac into an upper and a lower part the upper part extending from the barrel for manual compression after the removal of the cap avoiding the use of pressure bars, said ink sac parts leaving a wide open communication between the squeezing area and the lower part of the sac, and of comparatively large areas for the reception of a quantity of ink surpassing the quantity of ink available in pens having barrels of the same size, and a flexible air tube in said ink sac.

3. A fountain pen comprising an ink sac in its barrel having a restricted portion intermediate its ends, and a restricted lower end formed with said ink sac constituting an air tube, said restricted portion provided with openings for returning the ink from the upper part of the sac to its lower portion.

4. A fountain pen having an air tube comprising an ink sac in its barrel, a flexible tube formed within said sac, and a perforated connection between said flexible tube and ink sac.

5. A fountain pen including its feed comprising an ink sac in its barrel having a restricted portion intermediate its ends, a restricted flexible air tube adapted to engage the feed, a funnel-shaped connection between the part of the ink sac above the restricted portion and said flexible tube, said funnel-shaped connection having openings for returning ink from the upper portion of the sac into its lower part.

6. A fountain pen including its feed and comprising an ink sac in its barrel having a restricted portion intermediate its ends dividing said sac into a comparatively wide upper and lower portion, a restricted flexible air tube adapted to be drawn over the inner end of said feed, a connection having a plurality of openings connecting the flexible tube with the upper portion of the ink sac, said openings permitting the flow of ink from the upper portion of the sac into the lower portion thereof.
